Application filed October 17, 1895. Serial No. 566,012. Term of patent 3½ years.

To all whom it may concern:

Be it known that I, PHILEMON O. DICKINSON, a citizen of the United States, residing at Newark, in the county of Essex and State of New Jersey, have invented and produced a new and original Design for the Handles of Knives and Similar Articles, of which the following is a description, reference being had to the drawing accompanying and forming a part of the same.

This design relates to handles for table-ware and toilet articles, such as knives and similar articles.

The general outline of the handle is of an emphasized repandous form the handle broadening gradually from the shank to the middle portion A thereof, and then continuing by the somewhat narrower sinuous neck B to the end or heel of the handle C.

The face of the handle is broadly decorated with irregularly-disposed rococo figures, as shown.

What is claimed as new is—

The design for a handle for knives, and similar articles, substantially as shown and set forth.
